UNITED STATES PATENT OFFICE.

GEORGE E. DE VORE, OF LANSING, MICHIGAN, ASSIGNOR OF ONE-HALF TO
ALFRED BEAMER AND CHARLES H. MEAD, OF SAME PLACE.

WIRE-AND-SLAT-WEAVING MACHINE.

SPECIFICATION forming part of Letters Patent No. 628,774, dated July 11, 1899.

Application filed July 30, 1898. Serial No. 687,312. (No model.)

To all whom it may concern:

Be it known that I, GEORGE E. DE VORE, a citizen of the United States, residing at Lansing, in the county of Ingham and State of Michigan, have invented certain new and useful Improvements in Wire-and-Slat-Weaving Machines, of which the following is a specification, reference being had therein to the accompanying drawings.

10 My invention relates to machines of that class comprising a plurality of twisters for parallel pairs of binding-wires, a clamp or tension device for holding the slat at right angles thereto, means for reciprocating said twisters longitudinally upon the wires toward or from said clamp, and means for intermittently rotating said twisters for a definite number of turns, the whole arrangement being such that the slats may be successively 15 fed in between the wires when the twisters are drawn backward, then pushed into the clamp or tension device by the forward movement of the twisters, and the wires then twisted by the rotation of said twisters.

20 It is the object of my invention to render the whole operation of the machine automatic and continuous, to facilitate easy adjustment of parts, to vary the character of the work produced, and otherwise to improve the construction and operation of the machine; and to this end my invention consists, first, in the means employed for automatically feeding in the slats; further, in the mechanism employed for reciprocating the twisters and for 25 securing a corresponding and properly-timed movement of the slat-feeding mechanism, and, further, in the peculiar construction, arrangement, and combination of parts, all as more fully hereinafter described and claimed.

30 In the drawings, Figure 1 is a front elevation of my machine. Fig. 2 is a plan thereof. Fig. 3 is a side elevation. Fig. 4 is a diagram perspective showing drive connection for the feed mechanism, and Fig. 5 is a cross-section 35 centrally through the slat-feed carrier. Figs. 6 and 7 are sectional perspective views of the front and rear portions, respectively, of said carriers. Fig. 8 is a cross-section on line 40 xx , Fig. 6. Fig. 9 is a central longitudinal 45 section through one of the twisters. Fig. 10

is a cross-section on line ww , Fig. 9. Fig. 11 is a section on line yy , Fig. 1. Fig. 12 is an enlarged elevation of a portion of the slat-feed mechanism. Figs. 13 and 14 are, respectively, a plan and side elevation of the 55 mechanism controlling the reciprocation of the twisters, other parts of the machine being omitted. Fig. 15 is a cross-section on line zz of Fig. 14, showing, in addition, the carriage on which the twisters are supported. Fig. 16 is an elevation, partly in section, of the worm-gear connection shown in Fig. 15. Fig. 17 is a section on line 22 , Fig. 2. Fig. 18 is a longitudinal section through the slat-carrier rail. 60

A is the frame of the machine.

B B are twister-tubes extending longitudinally of the frame and journaled in forward and rear bearings C and D. The bearings C are sleeved upon the transverse shaft 70 E, mounted upon the wheels or rolls E', which are adapted to travel forward or backward upon a track E'', formed upon the top side bars A' of the frame. The bearings D are sleeved upon a cross-bar F, preferably formed 75 of two parallel rods, secured at their ends in brackets F' on the bars A'. These bearings C and D are laterally adjustably secured in position, the former by the adjustable collars a on the shaft E and the latter by the set-screws b, Fig. 9. 80

G are sprocket-wheels secured to sleeves G', which are feathered upon the twister-tubes B and extend through the bearings D, being secured therein by collars c, fastened to said 85 sleeves in rear of said bearings.

H is a shaft parallel to the twisters and journaled in suitable bearings in the lower part of the frame.

H' is a sprocket-wheel mounted on the shaft 90 in line with the sprocket-wheels G, and H'' is a sprocket-chain passing around all of said sprockets. The chain is held in engagement with said sprockets in the different adjusted positions by an idler G'', vertically adjustably secured upon a standard G', which is laterally adjustably secured upon the cross-bar F between the bearings D. 95

I is a drive-wheel sleeved upon the shaft H and adapted to be connected by a belt to any 100

suitable source of power. The hub of this wheel is suitably notched at each end to form a common member of two clutches, the other members of which are formed, respectively, by the sleeves I' and I^2 , the former being feathered and the latter being free to revolve upon the shaft H . At the forward end of the sleeve I' is secured a disk J , having a spiral groove J' formed in its forward face and extending from near the center to the periphery.

K is a rock-shaft extending transversely of the frame above the shaft H and journaled in suitable bearings.

K' is a tubular rock-arm secured to the rock-shaft K in line with the shaft H and extending downwardly toward said shaft.

K^2 is a rod extending longitudinally through the tubular rock-arm K' , having secured to its lower end the roller K^3 , adapted to engage with the spiral groove J' in the disk J .

K^4 is a stop adjustably secured to the rod K^2 above the tube K' , preferably by a screw-threaded engagement with said rod.

L is another rock-shaft extending across the frame above and slightly forward of the rock-shaft K . This rock-shaft is provided with a rock-arm L' , with which the upper end 30 of the rod K^2 has a sliding engagement, and at one end of the shaft is secured the upwardly-extending hand-lever L^2 . The sleeve I^2 has mounted thereon a drum or pulley I^3 .

M is a shaft extending longitudinally of the frame at one side thereof and slightly below the plane of the shaft E . This shaft is journaled in suitable bearings on the frame and carries the pulleys M' , M^2 , and M^3 , the middle pulley M^2 being fixed and the pulleys M' and M^3 loose upon said shaft.

N and N' are respectively straight and cross belts, connecting the pulley I^3 with the pulleys M' , M^2 , and M^3 .

N^2 and N^3 are belt-shifters, which are pivotally secured at their lower ends to ears 2 and 3, secured to the bar A^2 of the frame, and are provided with the laterally-extending rock-arms N^4 and N^5 .

O is a bar extending longitudinally of the frame in proximity to the rock-arms N^4 and N^5 and slidingly secured in bearings O' .

O^2 and O^3 are slotted cam-bearings secured to the bar O and with which pins on the rock-arms N^4 and N^5 engage.

P is a lever secured to the rock-shaft P' , journaled in the frame, which lever is connected at its lower end with the bar O and at its upper end to the bar Q , slidingly secured in bearings on the bar A' of the frame.

E^3 are pinions mounted upon the shaft E and engaging with racks E^4 , extending longitudinally of the frame above said pinions and secured to the frame-bars A' .

R is a worm-wheel secured to the shaft E in the vertical plane of the shaft M and engaging with the worm R' feathered upon said shaft M .

R^2 is a double bearing-frame adapted to hold the worm R' and worm-wheel R in proper engagement with each other and to permit the former to freely slide longitudinally upon the shaft M .

Q^2 and Q^3 are arms or standards extending upwardly from the bar Q and secured to said bar so as to have a limited sliding movement thereon.

Q^4 is a rod secured to the standard Q^2 and passing through an aperture in the standard Q^3 free to slide therethrough.

Q^5 is a set collar on the rod Q^4 , and Q^6 is a spring sleeved upon the rod Q^4 .

Q^7 and Q^8 are upwardly-extending arms or standards fixedly secured to the bar Q and through which the bar Q^4 slidingly passes.

Q^9 are rubber bumpers sleeved upon the rod Q^4 adjacent to the standard Q^7 and collar Q^5 .

Q^{10} is another rod slidingly secured in the standards Q^2 and Q^3 and having the collars Q^{11} at opposite ends thereof.

Q^{12} and Q^{13} are arms secured to the rod Q^{10} between the standards Q^2 and Q^3 and extending up into the path of the shaft E on opposite sides thereof.

Q^{14} and Q^{15} are lugs or detents attached to the sliding standards Q^2 and Q^3 and adapted to engage, respectively, with a hooked arm L^4 on the rock-shaft L and with the hooked arm of a bell-crank lever P^5 , the other arm of which extends upward into the path of the shaft E . The bell-crank lever P^5 is secured to a rock-shaft P^3 , extending across the frame of the machine and having secured to its other end the upwardly-extending hand-lever P^4 .

P^2 is a hand-lever secured to the rock-shaft P' .

K^5 is a rock-arm secured to the rock-shaft K and extending upward into the path of the shaft E .

K^6 is a rod pivotally connected at one end to the rock-arm K^5 and slidingly secured at its other end in the standard K^7 on the bar A' of the frame.

K^8 are collars secured to the rod on opposite sides of the standard K^7 .

K^9 is an arm on the rod K^6 , extending upward into the path of the shaft E .

M^4 is a pinion on the shaft M , meshing with a pinion S , journaled at the forward end of the frame.

S' is a sprocket-wheel connected with the pinion S , and S^3 is a sprocket-chain passing around said sprocket-wheel and extending across the front of the frame and around a corresponding sprocket-wheel S^3 at the outer end of a lateral extension of said frame. This lateral extension is preferably formed by a shelf or table A^3 , slightly below the plane of the twister-tubes and extending completely across the frame and about the same distance to one side thereof, being supported upon the bars A' and a standard A^4 at its outer end.

T is a slat-holder secured to the lateral ex-

tension of the shelf A³ slightly in rear thereof by the brackets T'. This holder is adapted to receive a pile of slats in vertical series, the lower slat resting on a slotted bottom plate 5 and a slot being formed in the end of the holder of sufficient width to allow this lower slat to pass therethrough.

Beneath the holder T is formed a track or 10 guide-rail T², preferably an angle-bar, which extends some distance over the main frame.

T³ is a head or carriage slidingly secured 15 on the rail T², to which is secured the slat-carrier or what I shall term the "shuttle" T⁴. This shuttle comprises two parallel bars d, spaced a distance apart slightly greater than 20 the width of the slats and being also of slightly-greater thickness than the slats. At their rear ends these bars are connected to a supporting-standard d' on the sliding head T³, which holds them in the plane of the lowest 25 slat in the holder. At the forward ends of the bars is formed a tapering shuttle-point comprising top and bottom plates d² and d³, between which the end of the slat is adapted to be engaged.

e and e' are oppositely arranged pivotal dogs secured to a lateral arm or bracket on the head T³ above the sprocket-chain S² and with which the lug S⁴ on said chain is adapted 30 to engage. These dogs are provided with releasing-arms adapted to respectively engage with the inclined lugs e² and e³, secured to the lower side of the shelf A³.

f is a dog pivotally secured upon the head 35 T³ in rear of the shuttle T⁴ and in line with the slot in the bottom of the slat-holder. f' is another similar dog secured to a sliding head T⁶ near the outer end of the slat-holder, which head is connected by the rod g with a 40 similar head T⁶, arranged some distance beyond the inner end of the slat-holder.

U are slotted U-shaped brackets secured 45 to the shelf A³, preferably a little to one side of the line of the twisters, the slots in these brackets being in line with the shuttle and the lower part of the bracket forming rests or bearings for the slat.

h and i are presser-springs secured to the upper portion of the brackets U, the former 50 in line with the center of the shuttle and the latter above the shelf A³.

U' are hooks secured to said guides and extending rearwardly.

The twisters B are preferably formed of 55 the outer tube j, the forward ends of which are provided with plugs k, having the central wire-passage l and, the eccentric passage m, respectively, for the main and binding wires.

n and o are tubes secured to the plug k in 60 line with the passages l and m and extending to the opposite end of the twister.

V are reels at the rear end of the frame 65 adapted to carry the coils of main wires from which the wires extend through the tubes n and the twisters.

W are small reels or spools carrying the binding-wires, which are preferably sleeved

upon the rear end of the twister-tubes and from which the wires are led into the tubes o of the twisters.

The parts being constructed and arranged 70 as shown and described, the operation of the machine is as follows: A pile of slats is first placed in the holder T and coils of wire on the reels V and spools W. The machine may

then be set in operation, motion being imparted to the wheel I and through the medium of the clutch-sleeve I² to the pulley I³.

From the pulley I³ motion is transmitted to the belts N and N', which in the initial position of the belt-shifters are respectively in engagement with the loose pulley M³ and the tight pulley M² on the shaft M.

The belt N will thus impart rotary motion to the shaft M in one direction, which through the medium of the worm R' and worm-wheel R will rotate

the shaft E, causing the pinions E³ to travel backward on the racks E⁴ from their initial position at the forward ends of said racks and carrying with them the shaft E, the bearing

C thereon, and the twisters B. At the same time motion from the shaft M is transmitted

through the medium of the gear-wheels M⁴ and S to the sprocket-wheel S' and the sprocket-chain S², causing the latter to travel

in a direction to carry the lug S⁴ inward. The lug S⁴ engages with the dog e and causes the head T³ to slide along the track T², carrying

with it the shuttle T⁴ and a slat therein which is pushed out of the holder by the dog f.

Before the shaft E and twisters B have reached

their rear position the shuttle has carried the slat between the main and binding wires, which extend forward from the twisters and through the slotted guides U, into the position

opposite the twisters, where it is to be deposited, at which point in the operation the releasing-arm of the dog e will strike against the cam e² and disengage said dog from the lug S⁴.

During the rearward movement of the shaft E the double bearing-bracket R² will cause

the worm R' to slide along the shaft M, while its feathered engagement therewith compels it to rotate with said shaft. Before the shaft E has completed its rearward movement it will

strike against the arm Q¹² on the rod Q¹⁰, pushing said rod backward and causing the collar Q¹¹ to carry the sliding standard Q² and rod

Q⁴ with it and placing a tension on the spring Q⁶, the rear end of which presses against the standard Q³.

The standard Q³ is, however, temporarily held from movement by the engagement of the hooked arm of the bell-crank lever P⁵ with the detent Q¹⁵; but in the further movement of the shaft E it will strike

against the upper end of said bell-crank lever and turn it sufficiently to disengage the hook from the detent. The spring Q⁶ will then

force the frame Q³ and rod Q backward by a quick movement, which is communicated to the lever P, which in turn will slide the bar O

forward, carrying with it the grooved cams O² and O³. The movement of these cams will rock the arms N⁴ and N⁵ of the belt-shifters

N² and N³ and cause them to shift the belt N from the loose pulley M' to the tight pulley M² and the belt N' from the tight pulley M² to the loose pulley M³, thus causing a reversal 5 in the movement of the shaft M. (See Fig. 3.) The shaft E in its rearward movement will also strike against the arm K⁹ on the rod K⁶, which will draw the arm K⁵ backward and rock the shaft K. This will rock the arm K' 10 forward, carrying the roll K³ in front of the disk J and allowing it to drop by gravity down until the stop K⁴ on the rod K² rests upon the upper end of the tubular arm K'. The reverse movement of the shaft M will cause the shaft 15 R and twisters B to travel forward and the sprocket-chain S² to travel in the reverse direction, the lug S⁴ engaging with the dog e' and carrying the sliding head T² and shuttle T⁴ outward. The slat which is in the shuttle 20 is, however, not carried out again therewith, as the springs h will press it against the slotted guide U, and as there are three pairs of these springs and guides two of them will always be holding the slat while the top and 25 bottom plates d² and d³ of the shuttle-point are drawn by the third guide and spring. In passing outward the bars d of the shuttle will pass upon opposite sides of the slat-holder T, while the dog f will pass through the slot 30 in the bottom plate. The shuttle will be fully withdrawn before the twisters have reached the position of the slat, and when withdrawn the releasing-arm of the dog e' will strike against the cam e³ and disengage said dog 35 from the lug S⁴. The further forward movement of the twisters will carry the slat forward in the slotted guides U and under the springs i, which will hold it during the operation of twisting. In the forward movement 40 of the shaft E it will strike against the arm Q¹³, which will move the rod Q¹⁰ forward, the collar Q¹¹ thereon carrying the sliding standard Q⁸ and sliding bar Q with it and compressing the spring Q⁶ against the collar Q⁵ 45 on the rod Q⁴. The latter is held from movement by the detent Q¹⁴ on the standard Q², which became engaged with the hooked arm L⁴ in the rearward movement of said standard. The movement of the bar Q will through 50 the medium of the lever P and sliding bar O impart a partial movement to the cams O² and O³, which are so shaped that the shifter N³ alone will be operated by this partial movement. This will shift the belt N' from the 55 tight pulley M² to the loose pulley and stop the rotation of the shaft M. Before the forward movement of the shaft E is stopped, however, it will strike against the arm K⁵ and rock the shaft K, which will rock the arm K' 60 backward and cause the roll K³ to push back the disk J, engaging the clutch-sleeve I', with the clutch-hub of the wheel I. This will start the rotation of the shaft H, which is communicated through the sprocket-and- 65 chain connection to the twisters B, causing them to twist the wires in rear of the slat. As the shaft H rotates the disk J will be turned

therewith, causing the roll K³ to travel outward in the spiral groove J' until it reaches the periphery of the disk, when a suitable returning device, such as the weighted lever X, will push the disk forward, disengaging the clutch members and stopping the rotation of the shaft. Simultaneously with the releasing of the clutch the hooked arm L⁴ will release the detent Q¹⁴ on the frame Q², this being caused by the raising of the rod K², which rocks the rock-arm L' and rock-shaft L, to which the arm L⁴ is secured. Upon the releasing of the detent the spring Q⁶ will move 70 the frame Q², and with it the rod Q, which through the connections before described will complete the movement of the cams O² and O³, causing the belt-shifter N² to shift the belt N from the loose pulley M' to the tight 75 pulley M² and start the rotation of the shaft M again in the reverse direction.

From the general description of the operation of the machine as above given it will be seen that its action is entirely automatic, the 80 only attention required being to replenish the pile of slats in the holder as often as necessary.

I wish now to call attention more specifically to certain features of construction and 90 the operation of certain parts as yet not fully described.

First, the construction of the holder for each of the binding-wires and the tension device therefor. The spool W is sleeved upon 100 the rear end of the sleeve G' free to rotate thereon. W' is a bar centrally connected to said sleeve G' in rear of the spool, the opposite arms of which extend outward beyond the flanges of the spool. W² is a curved tube extending around from tube o to one end of the cross-bar W'. W³ is a pin on the other end of said cross-bar, on which is pivotally secured a bifurcated lever W⁴, extending on opposite sides of the flange of the spool W. 105 One side of this lever is adapted to rest upon the wire on the spool and is compelled to travel inward as the wire is drawn off from the spool by the spring W⁵, which is so arranged as to exert a constant inward pull upon 110 said lever. W⁶ is an adjustable friction device on the outer arm of the lever W⁴, adapted to press against the flange of the spool and place tension upon the wire. In the operation of the machine this device will place a 115 perfectly uniform tension upon the binding-wire, as the friction device W⁶ is always applied to the spool at the same distance from the axis thereof as the wire leading off therefrom, and this will not decrease the tension 120 as the amount of wire on the spool diminishes. In order to provide means for readily winding the spool, I place upon each a bolt or catch W⁹, adapted to be engaged with a notch in a collar c, which is fast upon the 125 sleeve G' in rear of the bearing D. This will permit of driving the spool with the sprocket G and sleeve G' and winding the binding-wire on the spool W. In order to allow this

winding to be done independently on each of the spools, I provide means for preventing the rotation of the other spools by loosening the sprocket G upon the sleeves G'. This may 5 be done by providing a collar G³ at the forward end of the sleeve G' and a clamping-plate G⁴, secured to the sprockets by the screws G⁵ and adapted to either clamp said sprocket to the collar G³ on the sleeve G' or when the 10 screws are loosened to permit of its freely revolving thereon.

I wish also to call attention to the means employed in my machine for engaging the slat last inserted with the holding-clamps and 15 pushing the woven fabric forward. In former constructions of machines this has been done by the twisters pressing directly against the edge of the slat and forcing it into the holder. The effect of this is that the slat is generally 20 marred when the twisters first begin to rotate. In my construction I obviate this difficulty by placing pushers on the bearing C, which extend slightly beyond the forward end of the twisters and are adapted to bear against 25 the slat. These pushers are preferably in the form of sleeves C', surrounding that portion of each twister which extends beyond the bearing C, which sleeves are secured to hubs on said bearings. C² and C³ are collars secured 30 to the twisters on opposite sides of the bearing C to prevent end movement in said bearings.

Finally, I will describe more in detail the means for drawing the slats out of the holder 35 and engaging them with the shuttle. Just before the shuttle reaches its inmost position the sliding head T³ will strike against the sliding head T⁶, moving said head, and through the connecting-rod g also sliding inward the head T⁵, which carries the dog f'. As the 40 dog is adapted to engage with the lowest slat in the holder, it will push said slot before it, so that when the shuttle again moves outward the end of the slat will be projecting slightly 45 beyond the holder and free to engage with the socket in the point of the shuttle. The dog f will then engage with the rear end of said slat and when the shuttle again moves inward will carry the slat in the manner before 50 described.

As the slats may vary slightly in length, I provide means for keeping them in line at the inner edge of the fabric. This consists of a stop y, against which the end of the slat may 55 strike, and to prevent the dog f from doing injury in case the slat strikes said stop before the head T³ has completed its inward movement I secure said dog to said head by the yielding connection, such as the spring f'.

60 What I claim as my invention is—

1. In a wire-and-slat-weaving machine, the combination with the work-holder and the rotary twisters adapted to be reciprocated toward or from said holder, of mechanism for 65 feeding the slat endwise between said work-holder and twisters in the retracted position of the latter.

2. In a wire-and-slat-weaving machine, the combination with the work-holder and the rotary twisters adapted to be reciprocated toward and from said holder, of a slat-holder at one side of the machine, and a reciprocating shuttle adapted to carry a slat from said holder between said work-holder and twisters during the interval in which said twisters are 75 withdrawn.

3. A wire-and-slat-weaving machine comprising a work-holder, rotary twisters and a slat-holder, of mechanism for automatically feeding the slats from said holder, for intermittently reciprocating and intermittently rotating said twisters, timed to coöperate in a continuous operation.

4. In a wire-and-slat-weaving machine, the combination with the twisters, of mechanism 85 adapted to alternately longitudinally reciprocate and to rotate said twisters in continuous operation.

5. In a wire-and-slat-weaving machine the combination with the twisters, of mechanism 90 for intermittently longitudinally reciprocating, and mechanism for intermittently rotating said twisters, each adapted to automatically stop itself and start the other.

6. In a wire-and-slat-weaving machine, 95 mechanism for longitudinally reciprocating the twisters consisting of a traveling transverse shaft carrying bearings in which said twisters are journaled, a pinion on said shaft, a stationary rack with which said pinion engages, and means for rotating said shaft and pinion alternately in opposite directions.

7. In a wire-and-slat-weaving machine, mechanism for longitudinally reciprocating the twisters consisting of a transverse traveling shaft carrying bearings in which said twisters are journaled, rolls journaled upon said shaft on opposite sides of said twisters, stationary tracks upon which said rollers are adapted to travel, pinions on said shaft adjacent to said rolls, stationary racks above said pinions and in engagement therewith, and means for rotating said shaft alternately in opposite directions.

8. In a wire-and-slat-weaving machine, 115 mechanism for reciprocating the twisters, comprising a traveling transverse shaft, carrying the bearings in which said twisters are journaled, a pinion on said shaft, a stationary rack with which said pinion engages, a 120 longitudinally-extending drive-shaft adapted to be rotated alternately in opposite directions, and a worm-gear connection between said shafts adapted to travel with said transverse shaft and slide on said longitudinal 125 drive-shaft.

9. In a wire-and-slat-weaving machine, the combination with a traveling transverse shaft for reciprocating the twisters, and a longitudinal drive-shaft, the worm R' engaging therewith and feathered upon said drive-shaft and the connecting double bearings R² for the purpose described.

10. In a wire-and-slat-weaving machine,

- the combination with a traveling transverse shaft for reciprocating the twisters, a longitudinal shaft and a traveling worm-gear connection between said shafts, of tight and loose 5 pulleys upon said longitudinal shaft, oppositely-running drive-belts upon said pulleys, and a belt-shifter adapted to be operated by said traveling shaft at each end of its movement.
16. 11. In a wire-and-slat-weaving machine, the combination with a traveling transverse shaft for reciprocating the twisters, a longitudinal shaft and a traveling worm-gear connection between said shafts, of a reversible 15 drive-belt connection for said longitudinal shaft, a belt-shifter therefor, a spring-actuated device for said shifter extending into the path of said traveling shaft and adapted to be placed under tension thereby, a latch for 20 temporarily holding said shifter from movement and means for releasing said latch to permit the spring to actuate said shifter.
12. In a wire-and-slat-weaving machine, belt-shifting mechanism for controlling the 25 reciprocation of the twister-carriage, comprising the sliding bar Q, the standards Q² and Q³ thereon and having a limited sliding engagement therewith, the rod Q¹⁰ slidingly secured in said standards having the stop-collars Q¹¹ at opposite ends thereof and the arms Q¹² and Q¹³ on opposite sides of the twister-carriage projecting into the path thereof, the bar Q⁴ fixedly secured to one of said standards and slidingly secured to the other, the 30 spring Q⁶ thereon, the detents Q¹⁴ and Q¹⁵ on the standards and the latches P⁵ and L⁴ adapted to engage therewith, all arranged substantially as and for the purpose described.
13. In a wire-and-slat-weaving machine, 40 mechanism for automatically releasing the clutch for rotating the twisters, and simultaneously starting the reciprocating mechanism for said twisters, comprising the disk J on the movable clutch member having the spiral groove J' therein, a rock-arm, the rod K² slidingly secured thereto, the roller K³ on said rod engaging with said groove and adapted to run to the periphery of said wheel, and a trip for the reciprocating mechanism adapted to be 45 operated by the raising of said rod K².
14. In a wire-and-slat-weaving machine, the combination of the disk J having the spiral groove J' therein, the tubular rock-shaft K', the rod K² slidingly secured thereon, the roller 50 K³ at the lower end of said rod engaging with the groove J', and the adjustable stop K⁴ on said rod above said rock-arm, for the purpose described.
15. In a wire-and-slat-weaving machine, 55 the combination with a traveling transverse shaft for reciprocating the twisters, a longitudinal drive-shaft therefor, a traveling worm-gear connection between said shafts, and mechanism for reversing the rotation of said 60 drive-shaft, of an endless transverse chain-carrier, having a drive connection with said longitudinal shaft and a slat-carrying shuttle adapted to be reciprocated by said chain.
16. In a wire-and-slat-weaving machine, 70 slat-weaving mechanism comprising a transversely-extending track or way, a head slidably secured thereon, a slat-holding shuttle secured to and projecting forward from said head, a slat-holder having a slotted bottom plate, a dog on said sliding head adapted to 75 pass through said slot in the holder and force the lowest slat therefrom into said shuttle, and means for reciprocating said sliding head on said track.
17. In a wire-and-slat-weaving machine, 80 slat-feeding mechanism comprising a transversely-extending track or way, a head slidably secured thereon, a slat-carrying shuttle secured to said head and consisting of the forwardly-extending separated side bars and a 85 connecting-point having a socket for the end of the slat, a slat-holder having a slotted bottom plate and guides for said shuttle, a dog on said sliding head adapted to pass through said slot in said holder and force the lowest 90 slat out therefrom between the separated side bars of said shuttle, and means for reciprocating said head on said track.
18. In a wire-and-slat-weaving machine, 95 slat-feeding mechanism comprising a laterally-extending track or way, a head slidably secured thereon, a slat-carrying shuttle extending forwardly from said head consisting of separated side bars and a connecting socketed point, a slat-holder having a slotted bottom plate and guides for said shuttle, a dog on said head in rear of said shuttle adapted to pass through said slot, a second sliding head on said track in rear of said holder, a corresponding dog thereon, means for reciprocating said shuttle-head to carry the lowest 100 slat from said holder, and means for sliding forward said second head when said shuttle is near its forward position to force the end of the next slat from said holder.
19. In a wire-and-slat-weaving machine, 105 the combination with a slat-carrying shuttle comprising separated side bars, a connecting socketed point and a reciprocating head to which the rear ends of said bars are connected, 110 of supporting bars or bearings above which said shuttle passes, and presser-springs adapted to bear upon the slat in said shuttle and hold the same from movement when the shuttle is retracted.
20. In a wire-and-slat-weaving machine, 115 the combination with the longitudinally-reciprocating twisters and transversely-reciprocating slat-carrying shuttle, of the slotted or U-shaped guides through which said shuttle is projected, the presser-springs h secured thereto adapted to hold the slat while the shuttle is retracted, the presser-springs i forming the work-holding clamps adapted to receive the slat when pushed forward by the 120 twisters and hold the same during the operation of twisting, and the hooks U' for pre-

- venting the withdrawal of said slats by the backward movement of the twisters.
21. In a wire-and-slat-weaving machine, the combination with the reciprocating twisters, of pushers extending beyond the forward end of said twisters and adapted to carry the slat out of contact with the latter.
22. In a wire-and-slat-weaving machine, the combination with the reciprocating twisters and the traveling bearings in which said twisters are journaled, of pusher-sleeves secured to said bearings surrounding the forward ends of said twisters and projecting slightly beyond the same.
23. In a wire-twister, the combination with the spool or reel on which the wire is wound, of a tension device therefor, comprising a friction-brake applied to the flange of said spool and adapted to travel inward thereon as the wire on the spool diminishes.
24. In a wire-twister, the combination with the spool or reel on which the wire is wound, of a tension device therefor comprising a bifurcated pivotal arm embracing the flange of the spool, the inner member bearing against the wire on said spool, a friction-shoe on the outer member bearing against the flange of the spool, a pivot for said arm independent of said spool, and a spring for pressing said arm inward as the wire diminishes on the spool.
25. The combination with a rotary twister, of a wire-holding spool journaled upon said twister and the curved wire tube leading from the periphery of said spool into the end of said twister.
26. The combination of a plurality of wire-twisters, sprockets clamped thereon, a common drive-chain for all of said sprockets, a wire-holding spool loosely sleeved upon each of said twisters, and means for locking any one of said spools to its twister, and for loosen-

ing the sprockets of the other twisters, for the purpose of winding said spool.

27. The combination with a rotary wire-twister, of a wire-holding spool loosely sleeved thereon, and means for locking said spool to the twister for the purpose of winding.

28. The combination with a rotary and reciprocating wire-twister, of a sleeve in which said twister is feathered, a stationary bearing in which said sleeve is journaled, a sprocket-wheel secured to said sleeve on one side of said bearing, and a wire-holding spool journaled on said sleeve on the opposite side of said bearing.

29. The combination with a rotary and reciprocating wire-twister, of a sleeve in which said twister is feathered, a stationary bearing in which said sleeve is journaled, a sprocket-wheel clamped to said sleeve on one side of said bearing, a spool journaled on said sleeve on the opposite side of said bearing, and means for locking said spool to said sleeve.

30. A twister comprising a rotary tube, a plug or cap at one end thereof having central and eccentric apertures therethrough, and tubes within said outer tube connecting respectively with said apertures and leading to the opposite end of the twister.

31. In a wire-and-slat-weaving machine, the combination with the reciprocating slat-carrier, of a fixed stop against which the forward end of the slat is adapted to strike in the forward movement of the carrier, and a dog for pushing the rear end of the slat having a spring or yielding connection with said carrier.

In testimony whereof I affix my signature in presence of two witnesses.

GEORGE E. DE VORE.
